UNITED STATES PATENT OFFICE.

FLOYD A. RUCKMAN, OF FORT WAYNE, INDIANA.

DESIGN FOR A RADIATOR-FILLING CAP.

58,630.

Specification for Design.

Patented Aug. 2, 1921.

Application filed February 24, 1921. Serial No. 447,620. Term of patent 7 years.

To all whom it may concern:

Be it known that I, FLOYD A. RUCKMAN, a citizen of the United States, residing at Fort Wayne, in the county of Allen and State of Indiana, have invented a new, original, and ornamental Design for a Radiator-Filling Cap, of which the following is a specification, reference being had to the accompanying drawing, forming part thereof.

Figure 1 is a front elevation of a radiator filling cap showing my new design, Fig. 2 is a top view thereof, and Fig. 3 is an end view thereof.

I claim:

The ornamental design for a radiator filling cap as shown.

FLOYD A. RUCKMAN.
